UNITED STATES PATENT OFFICE.

THOMAS M. VAUGHAN, OF SALEM, OHIO, ASSIGNOR OF ONE-HALF TO HOWARD F. SCHUMACHER AND ONE-HALF TO CARL E. SCHUMACHER, BOTH OF HARTVILLE, OHIO.

ADJUSTABLE SCREEN AND PROCESS OF MAKING SAME.

Application filed December 29, 1925. Serial No. 78,139.

This invention relates to the manufacture of screens or ventilators and particularly to adjustable screens made of sheet metal. The object of the invention is to improve upon the design of screens of this type in order to economize in the manufacture and to simplify the design. A further object of the invention is to construct a metallic screen frame from a single piece or sheet of material so as to avoid brazing, welding or riveting of the joints. The screen structure is also designed to be reinforced by a heavy wire permanently seated in the edges of the frame and serving the double purpose of clamping the screen fabric in position and strengthening the frame. A further object of the invention is to improve upon the sliding construction by means of which the screen members are adjusted to fit the window openings.

Other objects and advantages will be apparent from the detailed description of the invention, it being understood that changes and modifications may be made in embodiments of the invention as the same is set forth in the claims. The various steps in the process of manufacture have been illustrated, showing the successive stages in the manufacture of the screen.

In the drawings:

Figure 1 is a sheet of metal of suitable size for the manufacture of one of the screen members showing the first and second steps in the manufacture;

Figure 1^a is a cross-section thereof on the line 1^a—1^a.

Figure 2 is a view showing the sheet of material at the termination of the third operation;

Figure 2^a is the cross-section thereof on the line 2^a—2^a;

Figure 3 is a view showing the sheet of material at the termination of the first bending operation;

Figure 3^a is a section thereof on the line 3^a—3^a;

Figure 4 is a view showing two of the finished screens in mating relation;

Figure 5 is a section on the line 5—5 of Figure 4;

Figure 6 is a section on the line 6—6 of Figure 4;

Figure 7 is a section on the line 7—7 of Figure 4; and

Figure 8 is a view showing a lock for preventing separation of the screen.

In all metallic screen structures of which I am aware, the screen frame members have been manufactured from a plurality of strips of material which have been united at the corners by welding, brazing or riveting. This construction is not strong and is expensive to manufacture. My improved screen structure is made from a single sheet of metal, thereby preserving the strength of the material to the best advantage.

In the manufacture of the screen, a piece of metal of approximately the correct size and shape is first cut from stock, this sheet being indicated by the numeral 1 in Figures 1 and 1^a. At the proper location inwardly from the edges of the sheet is then stamped the continuous wire receiving channel 2, this channel being substantially semi-circular in cross-section as shown in Figure 1^a.

The next step is shown in Figure 2 and consists in a trimming operation which stamps the sheet of material to its correct size and at the same time removes the center of the sheet of material to form the screen opening 3.

The next step is shown in Figures 3 and 3^a and comprises the first bending operation, at which time the edges of the sheet are bent upwardly as shown at 10.

The screen is now ready for the next and last operation in which the screen fabric is laid over the frame, the wire is pressed into the channel over the screen and the edges or flanges 10 on the upper and lower rails of one screen member are bent over, as at 14, to partially enclose the wire reinforcing and stiffening element 9.

The edges 10 along the upper and lower rails of the screen members are formed at right angles to the plane of the members and are bent to give the mating sliding features to the screen. This is done by forming the upper and lower edges of one member with grooves 12, while the other screen member is formed with depending flanges 13. When the two members are mated, the flanges 13 enter into the grooves 12.

The outer stiles of the screen members are formed by pressing the material around the wire 9 as shown in Figure 6.

The inner stiles are provided with flanges 15 which project inwardly in opposite direc-

tions to form stops which prevent the screen members from separating in one direction.

In order to prevent the separation of the screen members in the opposite direction, 5 stops are formed in the mating grooves and flanges upon the rails. These are initially formed during the third operation as illustrated in Figure 2. For this purpose the rails are notched, as shown at 18, leaving 10 small tongues on two corners. The opposite corners are cut away as shown at 20. When 15 the two members are placed in sliding relationship, the tongues 19 are bent downwardly into the grooves 12 on the screen member formed with the grooves. On the screen members which carry the flanges 13, the notches 20 project into the path of the tongues 19. The screen members are thus 20 prevented from separating after they are mated by the flanges 15 and by the tongues and notches 19 and 20 respectively.

It will be noted that the wire 9 holds the screen cloth 8 and is securely held within the channel 2 which extends about the entire 25 screen. It cannot be removed therefrom as the metal is pressed about it to such an extent that it cannot be released except by destroying the screen. The screen structure is made by simple stamping and bending operations, without any brazing, welding, riveting or soldering. The reinforcing wire 9 is located at the edge of the screen so that the greatest strength is obtained therefrom, and the sliding members are located between 30 the reinforcing wires or in transverse alignment therewith, so that the screen is easily adjusted and will not bend out of place. The invention may be used in the construction of cloth ventilators as well as wire fly- 40 screens, and certain features may be used in single screens as well as in the adjustable type.

What is claimed is:

1. A window screen composed of a single 45 sheet of metal having a single thickness of metal at the corners and having a continuous channel stamped therein adjacent the periphery of the sheet, the sheet having a central opening formed therein, a screen 50 cloth laid over the opening, and a wire received within the channel and serving to clamp the screen cloth therein and reinforce the screen.

2. A window screen composed of a single 55 sheet of metal having a single thickness of metal at the corners, and having a continuous channel stamped therein adjacent the periphery of the sheet, the sheet having a central opening formed therein, a screen 60 cloth laid over the opening, and a wire received within the channel and serving to clamp the screen cloth therein and reinforce the screen, the outer walls of the channel afterwards bent to restrict the channel at the 65 outer sides to permanently enclose the wire.

3. A window screen composed of a single sheet of metal having a single thickness of metal about the entire periphery of the screen, a central opening being formed in the sheet, a screen cloth over the central opening, and means for securing the screen cloth in stretched condition over the opening. 70

4. An adjustable window screen composed of two members each of which is composed of a single sheet of metal, a central opening being formed in the sheet and a continuous channel about the outer edge of the sheet, a screen cloth over the central opening, a screen-retaining and screen-stiffening wire seated within the channel, and interengaging sliding formations formed from the upper and lower rails of said members, said sliding formations being in transverse alignment with the wires. 75

5. A sliding window screen comprising two screen frame members formed with oppositely facing channels, a screen cloth, a screen-stiffening and screen cloth-retaining wire in each channel, the edges of the screen members being extended directly from the channels and at right angles to the planes of the members, one of the members being provided with a groove, and a mating flange in the edge of the other. 80

6. A sliding window screen comprising two screen members formed with oppositely facing channels, a screen cloth, a screen-stiffening and screen cloth-retaining wire in each channel, the edges of the screen members being bent inwardly to hold the wire within the channel and then outwardly at right angles to the plane of the screen, and mating sliding formations on the outwardly extending edges. 85

7. A sliding window screen comprising two screen members, substantially U-shaped channels formed in said screen members, the channels facing one another, a screen cloth, and a screen-cloth-retaining wire seated in each channel, the screen members being formed with edges extending toward each other and at right angles to the planes of the members, the edges being formed with mating grooves and flanges to constitute a 90 sliding connection between said members. 110

8. A metal window screen comprising a frame having a channel formed about its outer edge, a screen cloth, and a screen-cloth retaining wire in the channel, the outer wall of said channel being extended directly from the channel at right angles to the plane of the screen and formed into a sliding element. 120

9. In a sliding window screen comprising two members, one of said members having grooves along the opposite rails, the other member having flanges along the opposite rails which mate with the grooves to form sliding connections between the members and stops to prevent separation of the mem- 125 bers. 130

bers, the flanges being notched and the outer walls of the grooves being bent downwardly at the ends beyond the notches thereof into the grooves to form said stops.

5 10. In a sliding window screen comprising two members, one of said members having grooves along the opposite rails, the other member having flanges along the opposite rails which mate with the grooves to form sliding connections between the members and stops to prevent separation of the members, the outer walls of the grooves being bent downwardly at the ends thereof into the grooves to form said stops.

10 15. In an extensible window screen comprising a pair of screen frames having relative movement upon one another, a stop comprising flanges upon the ends of the frames

extending in opposite directions therefrom and adapted to strike one another to prevent separation of the frames in one direction, said flanges being formed from the metal of the screen frames.

20 25 30 12. In an extensible window screen comprising a pair of screen frames having relative movement upon one another, each frame consisting of a sheet of metal having a channel and a screen retaining wire seated in the channel, and a stop for preventing separation of the screen members in one direction comprising flanges formed from the sheet of metal and projecting outwardly of the planes of the screen frames and in opposite directions.

THOMAS M. VAUGHAN.
